UNITED STATES PATENT OFFICE.

JAMES M. DEAN, OF FORT WORTH, TEXAS.

PLOW SCRAPER AND CLEANER.

Application filed November 20, 1922. Serial No. 602,117.

To all whom it may concern:

Be it known that I, JAMES M. DEAN, citizen of the United States, residing at Fort Worth, in the county of Tarrant and State 5 of Texas, have invented certain new and useful Improvements in Plow Scrapers and Cleaners, of which the following is a specification.

This invention relates to new and useful 10 improvements in plow scrapers and cleaners.

In plowing the various kinds of land different conditions are encountered and the farmer loses more time and exerts more or less unnecessary labor, on account of these 15 various conditions. For instance in moist or wet soil it is necessary to frequently scrape off the dirt or mud which adheres to the plow blade, this being particularly true in the "black land" sections. In new and trashy land a large number of weeds, vines, 20 small limbs and roots are encountered and these catch under the beam and in front of the plow blade and must be frequently removed. Where the farmer is using a riding plow, he must dismount to scrape or 25 clean the plow under the practice now in general use which comprises pulling the trash away by hand and scraping off the dirt with a stick or other convenient thing.

The object of my invention is to provide 30 a single tool which may be used by the farmer for clearing and scraping a plow efficiently and expeditiously without dismounting from his seat and with the use of one hand only.

A further object is to provide a device for 35 pulling trash from in front of a plow without dismounting and without fatiguing effort.

Another object of the invention is to provide 40 means for engaging and supporting the tool on the frame of the plow within easy and convenient reach of the driver, whereby it may be quickly removed for immediate use.

A construction designed to carry out the 45 invention will be hereinafter described together with other features of the invention.

The invention will be more readily understood 50 from a reading of the following specification and by reference to the accompanying drawings, in which an example of the invention is shown, and wherein:

Fig. 1 is an elevation of a tool constructed 55 in accordance with my invention,

Fig. 2 is a longitudinal sectional view of the same, and

Fig. 3 is an enlarged detail of the supporting clip.

In the drawings the numeral 10 designates 60 a cylindrical handle which is comparatively short and is provided with a scraper blade 11 at one end, the over-all length of the tool being approximately two feet, altho this measurement may vary. The handle has an 65 enlarged hand grip 12 at its upper end, the blade being at the lower end. This grip enables the driver to more easily grasp and hold the handle.

The lower end of the handle has a transverse kerf 13 in which the shank 14 of the blade 11 is inserted and held by penetrating 70 rivets 15. The shank extends upwardly from the center of the blade. The blade has its upper edges concaved on each side 75 of the shank to form hooks 16 and the side edges 17 of the blade are curved upwardly and outwardly, the blade at the intersections of the hooks 16 and edges 17 being reduced to fingers 18 forming continuations of the 80 hooks. This construction amplifies the hooks and provides fingers or points which may be more readily engaged over the weeds, vines, limbs, etc., which are to be pulled from in front of the plow.

The bottom edge 19 of the blade is reduced 85 to form a cutter or scraper, but all other edges of the blade are blunt so as not to cut, particularly the hooks 16. The driver grasping the handle grip 12 leans over, 90 scrapes off the plow blade by pushing downwardly.

When the tool is not in use it should be supported in an accessible place and to do this I provide a spring clip 20 having its upper 95 end fastened to the handle below the grip by means of a pair of rivets 21 or other means. The lower end of the clip is curved outwardly from the handle so as to be readily sprung away from the handle and 100 engaged over a member of the plow frame and supported with the grip 12 in a convenient position to be grasped by the driver when he desires to use the tool. The clip is bowed over a pin 22 embedded in the handle 105 and projecting from the handle in position to be engaged by the clip when the same is pulled from the plow frame, whereby excessive vibration and the resultant crystallization of the steel, is obviated. The pin also 110

acts as a stop in pushing the handle downwardly on the plow frame.

In using the tool the driver grasps the same by the handle grip 12 and pulls it from the plow frame on which it is supported by the clip 20. The tool is turned so that one of the hook fingers 18 is turned downwardly which permits the driver to lean over and engage the said finger 18 and the hook 16 thereof over the weeds, vines, limbs, etc., which have accumulated in front of the plow under the beam. By pulling on the tool the foregoing accumulations are removed. The handle is made short so that the tool 15 may be easily handled with one hand.

After this operation, or if it is not necessary, the tool is turned so that the scraper edge 19 is brought into contact with the side of the plow blade and by pushing downwardly the mud or adhering soil is scraped from the said blade. After the tool has 20 been used it may be hung on the plow frame by engaging the clip 20 over the same. All of this is done without dismounting from

the plow seat and in an easy and expeditious 25 as well as efficient manner.

Various changes in the size and arrangement of the parts as well as modifications and alterations may be made within the scope of the appended claims. 30

What I claim, is:

In a plow blade scraper and cleaner, a handle having a hand grip at its upper end, a metal blade mounted at the lower end of the handle having its lower transverse edge 35 reduced to a scraper, the top edges of the blade on each side of the handle each being curved outwardly from the handle at a relatively wide degree and terminating in an outwardly directed blunt finger, whereby 40 weeds and the like may be quickly released from the top of the blade, and means intermediate the ends of the handle for detachably supporting it on the frame of an agricultural implement within easy reach of the 45 driver.

In testimony whereof I affix my signature.
JAMES M. DEAN.
